UNITED STATES PATENT OFFICE

143,002

DESIGN FOR A DRAPE FESTOON

Paul L. Hartnett, Leominster, Mass.

Application July 14, 1945, Serial No. 120,697

Term of patent 3½ years

(Cl. D21—1)

To all whom it may concern:

Be it known that Paul L. Hartnett, a citizen of the United States, residing at Leominster, in the county of Worcester and State of Massachusetts, has invented a new, original, and ornamental Design for Drape Festoon, of which the following is a specification, reference being had to the accompanying drawing, forming part thereof.

Fig. 1 is a view in front elevation; and

Fig. 2 is a view in side elevation of the drape festoon, showing my new design.

The essential and characteristic features of my design reside in the portions shown in full lines in the drawing.

I claim:

The ornamental design for a drape festoon, as shown and described.

PAUL L. HARTNETT.
